DESIGN FOR A KNITTED SWEATER

Leslie M. Sobo, New York, N. Y.

Application September 18, 1937, Serial No. 71,672

Term of patent 3½ years

To all whom it may concern:

Be it known that I, Leslie M. Sobo, a citizen of the United States and a resident of the city of New York, State of New York, have invented a new, original, and ornamental Design for a Knitted Sweater, of which the following is a specification, reference being had to the accompanying drawings, forming part thereof.

Fig. 1 is a front view of knitted sweater showing my design.

Fig. 2 is a rear view of the sweater shown in Fig. 1.

The characteristic feature of my design resides in the combination on the sweater disclosed in the ribbed pattern on the front waist portion as shown.

I claim:

The ornamental design for a knitted sweater, as shown and described.

LESLIE M. SOBO.
